UNITED STATES PATENT OFFICE.

HENRY J. GRELL, OF JOHNSON'S CREEK, WISCONSIN.

DESIGN FOR A SUPPORT FOR CARBOY-STANDS.

SPECIFICATION forming part of Design No. 26,221, dated October 27, 1896.

Application filed March 7, 1896. Serial No. 582,269. Term of patent 7 years.

To all whom it may concern:

Be it known that I, HENRY J. GRELL, a citizen of the United States, residing at Johnson's Creek, in the county of Jefferson and State 5 of Wisconsin, have invented and produced a new and original design for Supporting-Frames for Carboys; and I do hereby declare the following to be a full, clear, and exact description of the same, reference being had 15 to the accompanying drawing, forming a part thereof.

The drawing is a perspective view illustrating my design.

My design relates to the new and original 15 shape or configuration of the said supporting-frame for carboys.

The leading features of this design comprise a flat horizontal portion from which rise, at one edge thereof, vertical walls which 20 are of equal height at each end and for some

distance inward, and which gradually increase in height and rise up in rounded lines toward the center, where they unite in a vertical piece, beneath which is a triangular-shaped opening, while the top edge of said 25 vertical piece is rounded on the arc of a circle, this circle being continued on the outer side of said vertical piece, and from the center of said outer circular portion there projects outwardly a horizontal member which 30 is round in cross-section.

What I claim is—

The design for a supporting-frame for carboys, substantially as shown and described.

In testimony whereof I affix my signature 35 in presence of two witnesses.

HENRY J. GRELL.
